United States Patent Office

Des. 204,782
Patented May 17, 1966

204,782

CUP

Herbert Jourdan Wanderer, 606 Cedar Ave., Elmhurst, Ill.

Filed Aug. 17, 1965, Ser. No. 86,617

Term of patent 14 years

(Cl. D44—9)

Fig. 1

Fig. 2

FIG. 1 is a side elevational view of a cup embodying my new design; and

FIG. 2 is a bottom plan view thereof.

I claim:

The ornamental design for a cup, as shown and described.
